HINGED COVER CONTAINER

William A. Ringler, Wayne, Pa., assignor to National Folding Box Company, New Haven, Conn., a corporation of New Jersey

Application July 21, 1942, Serial No. 451,716

9 Claims. (Cl. 229—16)

This invention relates to hinged cover container, and more particularly to a container formed from paperboard material comprising a box part having a cover part hinged thereto adapted to telescope over the open end of the box part.

The hinged cover container constructed in accordance with this invention may be formed from a single blank of paperboard material of suitable strength and texture. Since only one side of the blank is presented as the outside face of the container, the paperboard forming the blank may be finished and imprinted on one side thereof only. The blanks may be cut and scored from large sheets or rolls of paperboard material on an automatic cutting and scoring machine. The box forming part of the blank comprises front, rear and side wall panels which are connected together to provide a tubular body. The box part is provided with a bottom end closure which may be formed by a bottom forming tuck-in flap extending from the lower end of the front or rear wall panel and tabs extending from the lower ends of the side wall panels.

The cover forming part of the blank comprises a top wall panel hinged to the upper edge of the rear wall panel of the box part, a front flange section hinged to the top wall panel, and a side wall forming section hinged to each end of the front flange section. An important feature of this invention comprises the provision of a pair of collapsing sections which are hingedly connected to the ends of the top wall panel and side wall forming sections of the cover part and to the upper ends of the side wall panels of the box part. The collapsing sections are so formed and constructed that upon closing movement of the top wall panel of the cover part, the front flange section is automatically drawn into a position substantially at right angles to the top wall panel of the cover part and the side wall sections are automatically drawn into a position substantially at right angles to the top wall panel and front flange section of the cover part.

In one form of the invention, each collapsing section is traversed by a pair of diagonally extending fold lines which meet substantially at a right angle so as to divide each collapsing section into three triangular shaped segments of substantially similar form and size. In another form of the invention, each collapsing section is traversed by a single diagonally extending fold line which divides the collapsing section into two triangular shaped segments of substantially similar form and size. In both forms of the inven-

tion, one of the triangular segments is hinged to the adjacent end of the top wall panel and is designed to fold inwardly to overlie the inside face of the top wall panel and another triangular segment is hinged to the adjacent edge of the side wall section of the cover part and is designed to fold inwardly to lie adjacent its associated triangular segment. In the first form of the invention above referred to, a third triangular segment is hinged to the upper end of the adjacent side wall panel of the box part and is designed to fold inwardly over the upper end of the box part.

When each collapsing section is fully collapsed, an inturned triangular tab of multi-ply thickness is presented. Complete collapse of these sections occurs when the top wall panel of the cover part has been swung into fully closed position. Collapsing movement of the sections operates to swing the front flange section of the cover part snugly over the outside face of the front wall panel of the box part and also operates to swing the side wall sections of the cover part snugly over the outside face of the adjacent side wall panels of the box part.

28 An abutment flap is hingedly connected to the front wall panel of the box part and a fixed abutment flap is secured to the inside face of the front flange section of the cover part. These abutment flaps cooperate to normally retain the cover part in closed position and are operative to resist opening movement thereof.

29 The blank is so formed and constructed as to permit assembly of the box part into collapsed shell form on an automatic gluing and folding machine at a high production rate. The collapsed assembled shells are substantially rectangular in outline and when stacked together may be shipped and stored in a minimum cubical space. The merchandise manufacturer can quickly close the bottom forming flap and tabs of the box part and insert the merchandise plug. By merely swinging the top wall panel of the cover part into closed position, the front flange section and side wall sections of the cover part

35 will automatically assume a snug position over the respective front wall panel and side wall panels of the box part. When the top wall panel has been swung to closed position, the abutment flaps will automatically snap into abutment so as to retain the cover part in normal closed position and resist opening movement thereof.

36 This improved hinged cover container is adapted for high speed economical production and when fully assembled is attractive and neat in appearance, strong and sturdy in construc-

tion, and adapted for the packaging of smoking tobacco, cigars, cigarettes and numerous other articles of merchandise which are desirably packed in hinged cover containers.

An object of this invention is to provide an improved hinged cover container which may be formed from a single blank of paperboard material by means of a few high speed assembly operations.

Another object of this invention is to provide a hinged cover container formed from paperboard material having a cover part so formed and constructed as to automatically fold and assemble itself when the top wall panel of the cover part is swung into closed position.

Another object of this invention is to provide an improved paperboard blank from which a hinged cover container may be automatically assembled on high speed folding and gluing machines.

A still further object of this invention is to provide a hinged cover container formed from paperboard material which is neat and attractive in appearance, strong and sturdy in construction and which is especially adapted for the packaging of various articles of merchandise which have heretofore been packaged in hinged cover containers formed from metal or similar rigid material.

Other objects of this invention will become apparent as the disclosure proceeds.

Although the novel features which are believed to be characteristic of this invention will be particularly pointed out in the claims appended hereto, the invention itself, as to its objects and advantages and the manner in which it may be carried out, may be better understood by referring to the following description taken in connection with the accompanying drawings forming a part thereof, in which:

Fig. 1 is a plan view of a prepared blank from which the improved hinged cover container may be formed;

Fig. 2 is a plan view of the major portion of the blank and showing the abutment flap associated with the cover part folded into adhesive engagement with the front flange section thereof;

Fig. 3 is a plan view of the blank as it appears after the front wall panel and its associated securing flap has been folded over the adjacent side wall panel and the rear wall panel of the blank;

Fig. 4 is a perspective view of the blank after the second side wall panel has been folded over the rear wall panel and adhesively secured to the securing flap so as to present a collapsed tubular shell ready for shipment and storage;

Fig. 5 is a perspective view of the collapsed shell shown in Fig. 4 after expansion into tubular form;

Fig. 6 is a perspective view of the expanded shell having the bottom wall flap folded into closed position to provide a closed end wall and presenting a fully assembled box part;

Fig. 7 is a perspective view of the container showing the cover part being swung into closed position, during which operation the cover part becomes self-assembling;

Fig. 8 is a perspective view of the fully assembled container with the cover part in closed position;

Fig. 9 is a vertical cross-sectional view through the assembled container having a merchandise

plug contained therein, this view being taken along line 9—9 of Fig. 8;

Fig. 10 is an enlarged vertical cross-sectional view through the upper portion of the container showing the cover part in partially raised position;

Fig. 11 is a perspective view of the upper portion of the container having a cover part provided with collapsing sections of somewhat modified construction;

Fig. 12 is a perspective view of the upper portion of the container shown in Fig. 11 showing the cover part being swung into closed position and undergoing automatic assembly;

Fig. 13 is a perspective view of the upper portion of the container showing the cover part fully assembled and swung into open position;

Fig. 14 is a perspective view of the upper portion of the assembled container, with the cover part in closed position and a sealing strip applied thereto; and

Fig. 15 is a vertical cross-sectional view of the upper portion of the container as it appears when viewed along line 15—15 of Fig. 14.

Similar reference characters refer to similar parts throughout the several views of the drawings and the specification.

The container forming blank as shown in Fig. 1 may be formed from paperboard material which need be imprinted on one side thereof only and which may be cut and scored at a high production rate on an automatic cutting and scoring machine. The blank comprises a box forming part *a* and a cover forming part *b* hinged to the box forming part along a transversely extending score line 11.

The box forming part comprises a front wall panel 1 hingedly connected along one side thereof by a longitudinally extending score line 6 to a side wall panel 3. The other side edge of side wall panel 3 is hingedly connected along a longitudinally extending score line 6' to the adjacent side edge of a rear wall panel 2. The opposite side edge of the rear wall panel 2 is hingedly connected along longitudinally extending score line 6'' to a side wall panel 4. A securing flap 5 at the opposite side of the blank is hingedly connected along a longitudinally extending score line 6''' to the front wall panel 1. A bottom forming flap 7 is hingedly connected along a transversely extending score line 8 to the lower end of front wall panel 1. A bottom tab 9 is hingedly connected to the lower end of each of the side wall panels 3 and 4 by a transversely extending score line 8''. The bottom forming flap 7 carries a tuck-in flap 7' hinged thereto along a transversely extending score line 8' and is designed to be inserted into the box part to lie against the inside face of the rear wall panel 2 and be frictionally gripped by the adjacent free edges of the inturned tabs 10.

An abutment flap 30 is hingedly connected to the upper end of the front wall panel 1 by a transversely extending score line 31. The abutment flap 30 may be provided with an abutment edge 32 extending substantially parallel with score line 31 and may also be provided with mitered ends 33, as illustrated in Fig. 1.

The cover forming part *b* of the blank comprises a top wall panel 18 hingedly connected to the upper end of the rear wall panel 2 along the transversely extending score line 11. A front flange section 12 is hingedly connected to the top wall panel 18 along a transverse score line 13 extending substantially parallel with score

line 11. An abutment flap 24 is hingedly connected to the front flange section 12 along a transverse score line 25 which may extend substantially parallel with score line 13. A side wall forming section 14 is hingedly connected to each end of the front flange section 12 along a longitudinally extending score line 15.

In the form of the invention illustrated in Figs. 1 to 10 inclusive, collapsing section 16 is hingedly connected to each end of the top wall panel 10 along a longitudinally extending score line 17. Each collapsing section 16 is also hingedly connected to the upper end of the adjacent side wall panel of the box part by a transversely extending score line 18 which is substantially in alignment with the transverse score line 11. The upper end of the collapsing section 16 is also hingedly connected to the adjacent side wall section 14 along a transversely extending score line 19, score line 19 being substantially in alignment with score line 13. The longitudinally extending score line 6' of the box part may be substantially in alignment with the adjacent longitudinally extending score lines 17 and 15 of the cover part and the longitudinally extending score line 6'' of the box part may be substantially in alignment with the other adjacent score lines 11 and 15 of the cover part.

Each collapsing section 16 is traversed by a collapsing score line 20 which extends from the adjacent end of the score line 13 diagonally across the collapsing section. Each collapsing section 16 is provided with a second collapsing score line 21 which extends from the adjacent end of the score line 11 diagonally across the collapsing section and meets the end of the companion score line 20 at substantially a right angle. The diagonally extending score lines 20 and 21 traversing each collapsing section 16 divide the collapsing section into three triangular shaped segments *w*, *x* and *y*, as illustrated more particularly in Fig. 1. The segments *w*, *x* and *y* are all substantially the same shape and size. The diagonally extending score lines 20 and 21 permit collapse folding of the triangular segments *w*, *x* and *y* when the top wall panel 10 is swung into closed position. The collapse folding of segments *w*, *x* and *y* operate to automatically fold the side wall sections 14 of the cover part into proper telescoped position over the side wall panels of the box part and automatically fold the front flange section 16 in proper telescoped position over the front wall panel 2 of the box part. It will be noted that the triangular segment *w* is hingedly connected to the adjacent end of the top wall panel 10 of the cover part, that the triangular segment *x* is hingedly connected by transversely extending score line 19 to the lower edge of adjacent side wall section 14 of the cover part, and the triangular segment *y* is hingedly connected along transversely extending score line 18 to the upper end of the adjacent side wall panel of the box part.

The blank as shown in Fig. 1 may be assembled into collapsed shell form on an automatic strip gluing and folding machine. In performing this assembly operation the blank preferably moves through the machine in the direction of the arrow 40 as shown in Figs. 1 and 2, and during this movement adhesive *g* is applied to the inside face of the abutment flap 24 associated with the cover part, following which the abutment flap 24 is folded about score line 25 into adhesive engagement with the inside face of the front flange section 12. The blank then moves in the

direction of the arrow 41 as shown in Fig. 3, and during this movement a strip of adhesive *g* is applied to the outside face of the securing flap 5, following which the front wall panel 1 is folded about the longitudinally extending score line 6 so as to overlie the inside face of the adjacent side wall panel 3 and a part of rear wall panel 2. During continued movement of the blank in the direction of the arrow 41, as shown in Fig. 3, the other side wall panel 4 is folded about the longitudinally extending score line 6'' so as to overlie the glued face of the securing flap 5 and is then pressed into firm adhesive engagement therewith. During the folding of the side wall panel 4, the adjacent collapsing section 16 folds along longitudinally extending score line 17 so as to overlie the inside face of the top wall panel 10, and the adjacent side wall section 14 also folds about longitudinally extending score line 15 so as to overlie the inside face of the front flange section 12, as indicated in Fig. 4. This assembled shell as shown in Fig. 4 is substantially rectangular in outline and a large number of these shells may be stacked one upon the other for shipment to and storage by the merchandise manufacturer in a limited cubical space.

When the containers are needed for the packaging of merchandise, the box part of the container may be finally assembled by expanding the collapsed shell, as shown in Fig. 4, into tubular form as shown in Fig. 5. The bottom tabs 9 are then folded inwardly so as to extend substantially parallel to the transverse score line 8. Bottom forming flap 7 is then folded to overlie the inturned bottom tabs 9, and the tuck-in flap inserted into the box part so as to lie against the inside face of the rear wall panel 2. The tuck-in flap is then frictionally gripped by the adjacent free edges of the inturned tabs 9. This bottom assembly operation may be quickly performed by hand if desired, in which event the merchandise manufacturer requires no end sealing machine. The box part *a* of the container, thus fully assembled, appears as shown in Fig. 6. A merchandise plug *P* may then be telescoped through the open end of the box part to assume its final position within the box part.

An important feature of this invention resides in the construction of the cover part whereby the cover part will become automatically assembled merely by swinging the top wall panel 10 of the cover part into closed position. As shown more particularly in Figs. 6 and 7, closing movement of the top wall panel 10 causes the sections 16 to automatically collapse and as they collapse the sections 16 automatically swing the front flange section 12 into position substantially at right angles to the top wall panel 10. Substantially simultaneously, the side wall sections 14 of the cover part are swung into position substantially at right angles to the front flange section 12. As the sections 16 collapse, each of the triangular segments *w* swing into a position to overlie the inside face of the top wall panel 10. Substantially simultaneously, each of the triangular segments *y* will swing inwardly from their associated side wall panels of the box part, and each of the triangular segments *x* will sandwich between their associated triangular segments *w* and *y*. When the cover part is in closed position each segment will present a three-ply in-turned triangular tab with the triangular segment *x* superimposed over the triangular segment *y* and with the triangular segment *w* superimposed over the triangular segment *x*. When

the cover part is in fully closed position, as shown in Fig. 9, the front flange section 12 will snugly overlie the front wall panel 1 of the box part and the side wall sections 14 will snugly overlie the outside face of the side wall panels of the box part. When the cover part is in closed position as shown in Fig. 9, the lower edge 32 of the hinging abutment flap 30 associated with the front wall panel of the box part will also abut the abutment edge 26 associated with the fixed abutment flap 24 of the cover part.

The collapsing sections 16 as thus formed will collapse smoothly and automatically and operate to swing the front flange section 12 of the cover part into snug overlapping relationship over the outside face of the front wall panel 1 of the box part and to swing the side wall sections 14 of the cover part into snug overlapping relationship over the adjacent side wall panels of the box part. The cover part may be readily swung into open position by applying an upward lifting force to the lower edge of the front flange section 12 of the cover part. When the cover part is swung into open position it will appear as illustrated in Fig. 5, with the top wall panel 10 and the front flange section 12 substantially in alignment with the rear wall panel 2 of the box part and with the side wall sections 14 and the collapsing sections 16 substantially in alignment with the adjacent side wall panels of the box part. When the cover part is thus fully open, free and unobstructed access to the contents is assured.

The container as illustrated in Figs. 11 to 15 may be formed similar to that illustrated in Figs. 1 to 10 inclusive and similar parts thereof need not be further described. The cover part b' is provided with collapsing sections 16' comprising a triangular segment w hinged to each end of the top wall panel 10 and a triangular segment x hinged to the lower edge of each of the side wall sections 14. The triangular segments x and w are hingedly connected along a diagonally extending score line 20 so as to make the segments x and w of substantially the same form and size. It will be noted that the triangular segment y employed in the container illustrated in Figs. 1 to 10 inclusive is eliminated from the container illustrated in Figs. 11 to 15 inclusive.

As illustrated in Figs. 12 and 13, closing movement of the top wall panel 10 causes the sections 16' to automatically collapse and as they collapse the sections 16' automatically swing the front flange section 12 into position substantially at right angles to the top wall panel 10. Substantially simultaneously the side wall sections 14 of the cover part are swung into position substantially at right angles to the front flange section 12. Each of the triangular segments w swings into position to overlie the inside face of the top wall panel 10. Substantially simultaneously each of the triangular segments x will swing inwardly so as to underlie its associated triangular segment w. When the cover part is in closed position each segment presents a two-ply turned triangular tab with the triangular segments x and w in overlying relationship. When the cover part is in fully closed position, as shown in Fig. 9, the front flange section 12 will snugly overlie the front wall panel 1 of the box part and the side wall sections 14 will snugly overlie the outside face of the side wall panel of the box part. When the cover part is in closed position as shown in Fig. 15, the lower edge 32 of the hinged abutment flap 30 associated with the front wall panel of

the box part will also abut the abutment edge 26 associated with the fixed abutment flap 24 of the cover part.

The fully assembled cover as shown in Fig. 14 may be maintained in fully assembled position by applying an adhesive strip 50 over the top wall panel 10 and side wall sections 14 of the cover part. Such adhesive strip may comprise a revenue stamp or adhesive tape which may extend over the side wall panels of the box part as illustrated in Fig. 14, to provide a sealed container. Upon breakage of the sealing strip 50 along the line of perforations 51, the cover part may be swung open as illustrated in Fig. 13 and the adhesive strip remaining attached to the top wall panel 10 and side wall sections 50 will then serve to maintain the cover part in fully assembled position. If desired, a similar adhesive strip may be applied to the cover part b of the container illustrated in Fig. 8.

In both forms of the invention the fixed abutment flap 24 and the hinged abutment flap 30 are so shaped and arranged as to cooperate to maintain the cover part in normally closed position and resist opening movement of the cover part. When upward lifting force is applied to the lower edge of the front flange section 12 of the closed cover part, stresses are imposed on the front wall panel 1 and the rear wall panel 2 of the box part, causing inward bowing of the upper ends thereof, as shown in Fig. 10. The resistance to opening continues until the hinged abutment flap 30, as shown in Fig. 10, extends at an obtuse angle to the front wall panel 1, when further resistance to opening is removed. Little or no resistance to the closing of the cover part is encountered. The hinged abutment flap 30 and fixed abutment flap 24 are so shaped and proportioned as to offer the desired resistance to normal opening of the cover part so that the cover part is retained in closed position and will not open during normal handling of the container.

This improved hinged cover container can be assembled into collapsed shell form at the box factory at high production speeds. Since the assembled collapsed shell is substantially rectangular in form, a large number of the collapsed shells may be packed together in a minimum cubical space. The merchandise manufacturer may complete the final assembly of the box part by expanding the shell, turning the bottom tabs inwardly and inserting the tuck-in flap. The merchandise plug may then be inserted into the box part either by hand or by means of an automatic filling machine. The cover part is so constructed and formed that it will assemble itself by simply swinging the top wall panel 10 of the cover part into closed position. When the top wall panel of the cover part is in closed position the front flange section thereof will be neatly arranged over the front wall panel of the box part with the cooperating abutment flaps clicked into abutment, and the side wall sections of the cover part will also neatly overlie the adjacent side wall panels of the box part. The container as thus constructed is neat and attractive in appearance, strong and durable in use, and is adapted for the packaging of numerous articles of merchandise.

While certain novel features of the invention have been disclosed and are pointed out in the annexed claims, it will be understood that various omissions, substitutions and changes may be made by those skilled in the art without departing from the spirit of the invention.

I claim:

1. An improved hinged cover container formed from paperboard material comprising, a box part having connected and enclosing front, rear and side wall panels and an open upper end, and a self-assembling cover part for said open upper end, said cover part having a top wall panel hingedly connected to the rear wall panel of the box part, a front flange section hingedly connected to the top wall panel and adapted to telescope over the front wall panel of the box part, a pair of side wall sections hingedly connected to the ends of said front flange section and adapted to telescope over the side wall panels of the box part, collapsing sections hinged to the adjacent ends of said top wall panel and side wall sections of the cover part, said collapsing sections being each traversed by a diagonally extending fold line dividing each collapsing section into hinged segments, at least one of said segments having a free edge, one of said segments being hingedly connected to the adjacent end of the adjacent side wall section and another segment being hingedly connected to the adjacent end of the top wall panel of the cover part whereby said collapsing sections are operative to automatically fold inwardly over the inside face of said top wall panel and swing the front flange section and the side wall sections of the cover part snugly over the respective front wall panel and side wall panels of the box part when the top wall panel is swung into closed position, and means to retain the cover part in closed position and resist opening movement thereof.

2. An improved hinged cover container formed from paperboard material comprising, a box part having connected and enclosing front, rear and side wall panels and an open upper end, and a self-assembling cover part for said open upper end, said cover part having a top wall panel hingedly connected to the rear wall panel of the box part, a front flange section hingedly connected to the top wall panel and adapted to telescope over the front wall panel of the box part, a side wall section hingedly connected to each end of said front flange section and adapted to telescope over the adjacent side wall panel of the box part, a pair of collapsing sections each traversed by a pair of diagonally extending fold lines dividing the section into hingedly connected triangular shaped segments and wherein at least two of said segments have a free edge, one of said segments being hingedly connected to the adjacent end of the adjacent side wall section, another segment being hingedly connected to the upper end of the adjacent side wall panel of the box part, and another segment being hingedly connected to the adjacent end of the top wall panel of the cover part, said sections being operative to collapse and automatically fold inwardly over the inside face of said top wall panel and swing the front flange section and the side wall sections of the cover part snugly over the respective front wall panel and side wall panels of the box part when the top wall panel is swung into closed position, and abutment means associated with the front flange section of the cover part and the front wall panel of the box part adapted to cooperate to normally retain the cover in closed position and operative to resist opening movement thereof.

3. An improved hinged cover container formed from paperboard material comprising, a box part having connected and enclosing front, rear and

side wall panels and an open upper end, said cover part having a top wall panel hingedly connected to the rear wall panel of the box part, a front flange section hingedly connected to the top wall panel and adapted to telescope over the front wall panel of the box part, a side wall section hingedly connected to each end of said front flange section and adapted to telescope over the adjacent side wall panel of the box part, and a pair of collapsing sections each defined by a pair of hingedly connected triangular segments both having a free edge, one of said segments being hingedly connected to the adjacent end of the adjacent side wall section of the cover part and the other hingedly connected to the adjacent end of the top wall panel of the cover part whereby the triangular segments of each collapsing section are operative to automatically fold inwardly over the inside face of said top wall panel and swing the front flange section and the side wall sections of the cover part snugly over the respective front wall panel and side wall panels of the box part when the top wall panel is swung into closed position, and abutment means associated with the front flange section of the cover part and the front wall panel of the box part adapted to cooperate to normally retain the cover part in closed position and operative to resist opening movement thereof.

4. An improved paperboard shell comprising, a box part having connected front, rear and side wall panels and an open upper end forming a collapsible tubular box body, and a self-assembling cover part for said open upper end, said cover part having a top wall panel hingedly connected to the rear wall panel of the box part, a front flange section hingedly connected to the top wall panel and adapted to telescope over the front wall panel of the box part when the box part is erected, a side wall section hingedly connected to each end of said front flange section and adapted to telescope over the adjacent side wall panel of the box part when the box part is erected, collapsing sections hinged to the adjacent ends of said top wall panel and side wall sections of the cover part, said collapsing sections being each traversed by a diagonally extending score line dividing each collapsing section into hinged segments at least one of which has a free edge, one of said segments being hingedly connected to the adjacent end of the top wall panel and another to the adjacent end of the side wall section of the cover part whereby said collapsing sections are operative to automatically fold inwardly over the inside face of said top wall panel and swing the front flange section and the side wall sections of the cover part snugly over the respective front wall panel and side wall panels of the erected box part when the top wall panel is swung into closed position, and abutment means associated with the front flange section of the cover part and the front wall panel of the box part adapted to cooperate to normally retain the cover part in closed position and operative to resist opening movement thereof when the container is assembled.

5. An improved paperboard shell comprising, a box part having connected front, rear and side wall panels and an open upper end forming a collapsible tubular box body, and a self-assembling cover part for said open upper end, said cover part having a top wall panel hingedly connected to the rear wall panel of the box part, a front flange section hingedly connected to the

top wall panel and adapted to telescope over the front wall panel of the box part when the box part is erected, a side wall section hingedly connected to each end of said front flange section and adapted to telescope over the adjacent side wall panel of the box part when the box part is erected, and a pair of collapsing sections each defined by three hingedly connected triangular segments which are in turn hingedly connected to the adjacent end of the top wall panel and the adjacent end of the side wall section of the cover part and the adjacent end of the side wall panel of the box part, at least two of the triangular segments of each collapsing section having free ends, the triangular segments of each collapsing section being operative to automatically fold inwardly over the inside face of said top wall panel and swing the front flange section and the side wall sections of the cover part snugly over the respective front wall panel and side wall panels of the erected box part when the top wall panel is swung into closed position, and abutment means associated with the front flange section of the cover part and the front wall panel of the box part adapted to cooperate to normally retain the cover part in closed position and operative to resist opening movement thereof when the container is assembled.

6. An improved paperboard shell comprising, a box part having connected front, rear and side wall panels, an open upper end providing a collapsible tubular box body, and a self-assembling cover part for said open upper end, said cover part including a top wall panel hingedly connected to the rear wall panel of the box part, a front flange section hingedly connected to the top wall panel and adapted to telescope over the front wall panel of the box part when the box part is erected, a side wall section hingedly connected to each end of said front flange section and adapted to telescope over the adjacent side wall panel of the box part when the box part is erected, and a pair of collapsing sections connecting the adjacent ends of said top wall panel and side wall sections of the cover part, each of said collapsing sections being traversed by a diagonally extending fold line dividing the section into a pair of segments one of which is hingedly connected to the adjacent edge of a side wall section and the other hingedly connected to the adjacent end of the top wall panel of the cover part, each of the paired segments of each collapsing section having a free end, the segments forming the collapsing sections being foldable inwardly over the inside face of the top wall panel so as to present a multi-ply inturned tab which is automatically assembled when the top wall panel of the cover part is swung into closed position over the erected box part.

7. An improved paperboard blank adapted for assembly into a hinged cover container comprising a box-forming part having front, rear and side wall panels hingedly connected in side-by-side relationship, a bottom forming panel hinged to the lower end of one of said first named panels, and a self-assembling cover part having a top wall panel hinged to the upper end of the rear wall panel of the box part, a front flange section hinged to said top wall panel, a pair of side wall sections for the cover part each hingedly connected to the adjacent end of said front flange section, and a collapsing section hingedly con-

nected to each end of said top wall panel and the adjacent side wall section of the cover part, each of said collapsing sections being traversed by a fold line which serves to divide each collapsing section into generally triangular shaped collapsing segments, at least one of said segments of each collapsing section having a free edge, abutment means fixed to the inside face of said front flange section, and abutment means secured to the upper edge of the front wall panel of the box part, said abutment means being adapted to cooperate to retain the cover part in closed position when the blank has been assembled into container form.

8. An improved paperboard blank adapted for assembly into a hinged cover container comprising a box-forming part having front, rear and side wall panels hingedly connected in side-by-side relationship, a bottom forming panel hinged to the lower end of one of said first named panels, and a self-assembling cover part having a top wall panel hinged to the upper end of the rear wall panel of the box part, a front flange section hinged to said top wall panel, a pair of side wall sections for the cover part each hingedly connected to the adjacent end of said front flange section, and a collapsing section hingedly connected to each end of said top wall panel and the adjacent side wall section of the cover part and the adjacent side wall panel of the box part, each of said collapsing sections being traversed by a pair of diagonally extending fold lines which meet at substantially a right angle and serve to divide each collapsing section into triangular shaped segments, at least two of the segments of each collapsing section having a free edge, abutment means fixed to the inside face of said front flange section, and abutment means secured to the upper edge of the front wall panel of the box part, said abutment means being adapted to cooperate to retain the cover part in closed position when the blank has been assembled into container form.

9. An improved paperboard blank adapted for assembly into a hinged cover container comprising a box-forming part having front, rear and side wall panels hingedly connected in side-by-side relationship, a bottom forming panel hinged to the lower end of one of said first named panels, and a self-assembling cover part having a top wall panel hinged to the upper end of the rear wall panel of the box part, a front flange section hinged to said top wall panel, a pair of side wall sections for the cover part each hingedly connected to the adjacent end of said front flange section, and a collapsing section hingedly connected to each end of said top wall panel and the adjacent side wall section of the cover part, each of said collapsing sections being traversed by a diagonally extending fold line which serve to divide each collapsing section into two substantially triangular shaped segments, both of the segments of each collapsing section having a free edge, abutment means fixed to the inside face of said front flange section, and abutment means secured to the upper edge of the front wall panel of the box part, said abutment means being adapted to cooperate to retain the cover part in closed position when the blank has been assembled into container form.
